NOISE SUPPRESSION DEVICE

Deslonde R. de Boisblanc, Bartlesville, Okla., assignor to Phillips Petroleum Company, a corporation of Delaware

Application March 7, 1949, Serial No. 80,086

23 Claims. (Cl. 179—171)

1

This invention relates to a noise suppression device and to a noise suppression circuit incorporated in said device.

In the radio or phonograph reproduction of music or other programs, difficulties arise from interference with the program by noise. This is particularly true of phonograph reproduction wherein a substantial amount of needle scratch is normally heard in the output of the reproducing set. These noises, such as needle scratch, are of substantially constant amplitude throughout the length of the recording and, hence, they are particularly noticeable during quiet passages when the signal amplitude is low.

In accordance with the present invention, I make use of the frequency reproduction characteristics of the human ear in eliminating unwanted noises. When a musical program is heard at a high amplitude level, the ear is sensitive to a wide range of audio frequencies, for example, from 50 to 15,000 cycles per second whereas, at low signal amplitudes, the ear may respond only to frequencies within a range of from 200 to 2500 cycles per second. Hence, signals outside the range of 200 to 2500 cycles per second may be eliminated at low signal amplitudes without detracting from the realism of the musical reproduction and, by eliminating these frequencies, a major portion of the unwanted noises, such as needle scratch, are eliminated. During periods of higher signal amplitude, the presence of noise is not noticeable due to the high signal level.

Various attempts and proposals have been made to provide a system where the frequency range depends on amplitude in such fashion as to discriminate against unwanted noises in the manner just indicated. One such proposed system involves the use of a biased rectifier tube to eliminate signals of less than a predetermined amplitude and, when this predetermined amplitude is above the maximum noise level, both the noise voltages and a portion of the signal are eliminated. This system thus completely eliminates signals of low amplitude, and produces some distortion of high amplitude signals due to the elimination of a part of the signal voltage. It has also been proposed to reduce noise by introducing a single non-linear element in series with the load circuit of an amplifier, this element offering a higher resistance to noise and signals of low amplitude while establishing a low resistance for signals of high amplitude. In this system too, it will be noted that a portion of the desired low amplitude signals are eliminated together with the noise, while the non-linear element produces

2

some distortion of the high amplitude signals. It has also been proposed to incorporate high pass and low pass filters in the amplifier circuits of the reproducer, each filter including a variable reactance which adjusts the cut-off frequency of the filter in accordance with signal amplitude. The provision of such variable reactances involves the use of complicated and expensive circuits, making it difficult to incorporate such units in existing reproduction systems, or even in new reproducing units.

It is an object of this invention to provide an improved and greatly simplified device for eliminating background noise in a radio or phonograph.

It is a further object to provide such a noise suppression device in which non-linear resistance elements are combined with an impedance element to eliminate unwanted noise voltages without detracting from the realism of the program to be reproduced.

It is a still further object to provide a circuit which is simple to construct, which may be readily added to existing radio and phonograph units, and which utilizes a small number of standard circuit components.

Various other objects, advantages and features of the invention will become apparent to those skilled in the art from the accompanying drawings, in which:

Figure 1 is a schematic circuit diagram of a reproduction unit embodying my novel noise suppression unit;

Figure 2 is a simplified schematic diagram of the noise suppression circuit;

Figures 3, 4 and 5 are schematic circuit diagrams showing modified noise suppression circuits; and

Figures 6, 7 and 8 are graphs illustrating features of the invention.

Referring now to the drawings in detail, and particularly to Figure 1, I have shown an electron tube 10 of the triode type, the control grid of which is connected to the arm of a potentiometer 11 shunted across a pair of input terminals 12, 13, the latter terminal being grounded, as indicated at 14. The anode of tube 10 is supplied with operating potential from a positive power supply terminal 15 and the cathode is connected to ground through a noise suppression circuit 16 connected in series with an integrating circuit 17. The noise suppression circuit comprises a pair of series connected non-linear resistances 18, 20 having similar voltage-resistance characteristics. Preferably, these resistances are of the Thyrnite

type and their resistance varies non-linearly in accordance with the voltage impressed thereacross. That is, the relation between the current and impressed voltage across one of the Thyrite resistances is not expressed by Ohms law, but rather by the relationship $I=Ke^n$, where I represents current, n is a constant greater than unity, and e represents voltage.

The voltage-resistance relationship is shown by the graph, Figure 6, in which the abscissa represents resistance and the ordinate represents voltage. From this graph, it will be noted that the resistance of each of the Thyrites 19, 20 increases in accordance with a power function as the voltage decreases. The graph shows a typical voltage-resistance characteristic but it will be understood that the curve may be made steeper or flatter by suitable choice of the kind and arrangement of material in the non-linear resistances. The response of such resistances to voltage changes is practically instantaneous and there is no time lag or averaging effect as is noted with non-linear resistances of the hot wire type. This latter type of resistance, however, may be used in some cases with resultant elimination of the integrating circuit of the present invention.

The noise suppression circuit also includes an impedance 21 shunted across non-linear resistance 20, this impedance by-passing a portion of the signal voltage appearing across resistance 20, and the amount of voltage thus by-passed is dependent upon the frequency of the incoming signal. It will be noted that the resistances 19, 20 and impedance 21 constitute a filter, the pass band of which is determined by the ohmic value of resistances 19 and 20, for a given value of impedance 21.

The integrating circuit 17 includes a potentiometer 22, the fixed terminals of which are shunted by a condenser 23, and the arm of which is connected to an output terminal 24, the other output terminal 25 being connected to the junction between non-linear resistances 19 and 20. One terminal of potentiometer 22 is grounded, and the other terminal is connected by a lead to the adjacent end of non-linear resistance 20. The integrating circuit 17 is supplied with amplified, rectified signal voltage from the input terminals 12 and 13. To this end, input terminal 12 is connected by a lead 27 and a coupling condenser 28 to the control grid of an amplifier tube 29. This control grid is also connected to ground by a grid resistor 30 which is shunted by a condenser 31 while the cathode of the tube is connected to ground through a biasing resistor 32 which is shunted by a by-pass condenser 33. The anode of tube 29 is connected to a positive power supply terminal 34 through a resistance 35, and it is further connected to an input lead of integrating circuit 17 through a coupling condenser 36 and a rectifier 37, the junction between the latter units being grounded through a resistor 38.

The operation of the described circuit may be better understood by reference to Figure 2 which shows only the noise suppression circuit. An input signal impressed across the resistances 19, 20 produces an output voltage across the unit 20, 21 which is decreased in amplitude in accordance with the ratio between the parallel complex impedance of units 20 and 21 and the total complex impedance of the circuit. In this connection, it will be noted that the circuit functions as a voltage divider, resistance 19 forming one section of the divider, and the units 20, 21 forming

the other section. For example, assuming resistances 19, 20 to be of equal value, and assuming a signal frequency such that the impedance 21 is very large compared to the ohmic value of resistance 20, it will be apparent that the amplitude of the output signal is 50 per cent of the amplitude of the input signal.

At a second signal frequency, where the impedance 21 is equal to the ohmic value of resistance 20, the impedance of unit 20, 21 is lowered, and the output signal amplitude is less than 50 per cent of the input signal amplitude.

At a third signal frequency one octave removed from the second signal frequency, the impedance 21 is equal to one-half the ohmic value of resistance 20, thereby producing an additional drop in the output signal strength.

Thus, within the range between the first and second frequencies, no detectable attenuation of the signal is produced, while beyond the second or cut-off frequency, there is an attenuation which approaches the ultimate slope of six decibels per octave.

Where attenuation of unwanted high frequency signals is desired, the impedance 21 is a condenser while, when attenuation of low frequency signals is desired, the impedance 21 is an inductance. A typical output amplitude-frequency relationship for high frequency attenuation is shown by the plot 40, Figure 7, from which it will be noted that attenuation of the signal from its initial or input amplitude 41 is very small (less than three decibels), until cut-off frequency 42 is reached, after which the signal is attenuated about six decibels per octave as the frequency is increased.

The plot 40 represents the frequency-amplitude relationship when the signal amplitude is very low and, consequently, the ohmic value of resistances 19, 20 is correspondingly high. As a result, the cut-off point 42 where the reactance of condenser 21, which decreases with increasing frequency, equals one-half the relatively high ohmic value of resistance 20 at a low frequency. The values of the circuit components are such that all high frequency signals which are inaudible to the ear at such low amplitude levels are attenuated and eliminated. The signals thus eliminated would be inaudible even in the absence of noise. But the high level scratch noise which would be above the threshold level is attenuated, thus improving the apparent signal to noise ratio.

When the amplitude of the input signal is increased, the voltage across resistances 19, 20 is increased, and their resistance is decreased, in accordance with Figure 6. As a result, the cut-off point 47 at which the reactance of condenser 21 equals half the lower ohmic value of resistance 20 occurs at a higher frequency. This is shown by the plot 45, Figure 7, in which the original high signal amplitude 46 decreases little with frequency until the cut-off point 47 is reached, this cut point being at a substantially higher frequency than the cut-off point 42, of the low amplitude curve 40. Thus, where impedance 21 is a condenser, the cut-off frequency increases as the signal amplitude becomes greater, and the cut-off frequency decreases as the amplitude is reduced. In this manner, unwanted high frequency noise signals are eliminated from the output of the reproducer under the conditions for which they are most objectionable.

The cut-off frequency of the circuit is thus

controlled by the ohmic value of the resistances 19, 20 which, in turn, varies in accordance with the amplitude of the incoming signals. The rate at which the cut-off frequency increases with amplitude is dependent upon the voltage-resistance characteristics of the non-linear resistances 19, 20. If the resistance of these units decreases rapidly with increasing signal or applied voltage, the cut-off frequency increases rapidly with signal amplitude. Likewise, if the resistance of units 19, 20 decreases slowly with increasing signal or applied voltage, the cut-off frequency increases slowly as the signal level increases.

It may be considered that the resistances 19, 20 and condenser 21 constitute a low pass filter, the cut-off frequency of which is adjustable, in response to changes in signal amplitude, by the resultant variations in resistance of the units 19 and 20.

Where it is desired that unwanted low frequency signals be removed from the output of the reproducer, rather than unwanted high frequency signals, the impedance 21 is an inductance, rather than a condenser. In this case, the impedance of the inductance is high at normal signal frequencies but decreases with decreasing frequency. The inductance of the unit 21 is so adjusted that its impedance is equal to that of resistance 20 at a predetermined cut-off frequency, and for a preselected signal amplitude. Accordingly, at the cut-off frequency, the signal attenuation is three decibels, which is the smallest volume change detectable by the human ear while, at higher frequencies, the attenuation is less than three decibels and is not detectable by the human ear. At frequencies below the cut-off frequency, the signal is attenuated three decibels per octave due to the progressively decreasing impedance of the inductance, with respect to the ohmic value of resistors 20 and 21.

When the amplitude of the input signal is increased, the voltage across resistances 19, 20 is increased, and their resistance is decreased, in accordance with Figure 6. As a result, the cut-off frequency at which the impedance of inductance 21 equals the lower ohmic value of resistance 20 is decreased. Thus, where impedance 21 is an inductance, the cut-off frequency decreases as the signal amplitude becomes greater, and the cut-off frequency increases as the amplitude is reduced. In this manner, unwanted low frequency, low amplitude noise signals are eliminated from the output of the reproducer. Here again, the rate at which the cut-off frequency decreases with amplitude is dependent upon the voltage-resistance characteristics of the non-linear resistances 19, 20 and the elements 19, 20, 21 in this case constitute a high pass filter, the cut-off frequency of which decreases with increasing amplitude, due to the voltage-resistance relationship established by resistances 19 and 20.

Broadly speaking, therefore, it will be apparent that a voltage representative of signal amplitude impressed across the resistances 19 and 20 varies the impedance thereof to shift the preselected frequency range within which signals appearing across the unit 20, 21 are attenuated by the impedance 21. That is, the signal appearing across the unit 20, 21 is attenuated by a decrease in the reactance of the impedance 21 at all frequencies within a preselected frequency range, and the impressed voltage across the resistances 19, 20 varies the ohmic value thereof to shift said preselected frequency range within the frequency spectrum in accordance with the signal amplitude.

It will be apparent that the circuit 19, 20, 21 of Figure 1 operates in the manner described in connection with Figure 2. Signal voltage is impressed across the resistances 19, 20 by their inclusion in the cathode circuit of tube 10, and this voltage appears across the resistance-impedance unit 20, 21 and across the output terminals 24, 25 which are effectively connected across this unit through a portion of potentiometer 22. A direct voltage representative of average signal amplitude is applied across the integrating circuit 22, 23 to change the bias on tube 10. This bias voltage, as stated, controls the location of the attenuation range in the frequency spectrum by varying the current flow through non-linear resistances 19 and 20 and tube 10. The time constant of the integrating circuit, of course, determines the rapidity with which the cut-off frequency shifts in response to variations in amplitude of the incoming signal. The potentiometer 22 forms a bridge circuit with resistance 20 and the output load to balance out voltage surges resulting from sudden changes in signal amplitude.

Accordingly, the noise suppression circuit operates in the manner described in connection with Figure 2, signal voltage being impressed across the resistances 19, 20 from tube 10, a direct voltage proportional to average signal amplitude being impressed across said resistances by the integrating circuit 17, and the output appearing across terminals 24, 25 which are effectively connected in shunt with the impedance-resistance unit 20, 21.

As stated, when impedance 21 is a condenser, the noise suppressor circuit cuts out high frequency signals which are beyond the limits of audibility of the human ear at each particular amplitude level of the incoming signals and, when impedance 21 is an inductance, the same effect occurs with respect to low frequency signals. In the majority of cases, use of a high frequency filter is sufficient to bring about a substantial decrease in the signal to noise ratio and, in fact, to suppress the noise to such an extent that it is not noticeable in the output of the reproducer. However, it will be apparent that two similar circuits may be used in a single reproducer, if desired, one to suppress unwanted high frequency components and the other to suppress unwanted low frequency components.

A modified noise suppression circuit is shown in Figure 3. In this circuit, the amplifier, rectifier, and integrating circuit of Figure 1 are eliminated so that the impedance of the non-linear resistances is controlled by the instantaneous signal voltage rather than by an average or integrated rectified signal voltage, as in Figure 1. To this end, the integrating circuit 17 is eliminated and the series connected non-linear resistances are connected directly between the cathode of tube 10 and a ground terminal 50. The output voltage appears across terminals 51 and 52 which are connected across the resistance-impedance units 20 and 21. The operation of this circuit is similar to that of Figure 1, except that the ohmic value of the resistances 19, 20 is controlled by the instantaneous signal voltage rather than by the direct voltage produced by an integrating circuit, such as circuit 22, 23 of Figure 1.

The distortion encountered with this type of circuit is very small since a cathode follower arrangement is used so that the voltage appearing between the cathode of tube 10 and ground is always the same as the voltage impressed be-

tween the control grid of tube 10 and ground. As a result, neglecting the impedance 21, the output voltage is always one-half the input voltage if the resistances 19, 20 are of equal ohmic value or, alternatively, it bears a fixed ratio to the input voltage if these resistances are not of equal ohmic value. The only type of distortion encountered with the present circuit is that illustrated by Figure 8 wherein, for purposes of example, an input signal is shown consisting of a low frequency component 55 and a high frequency component 56 which are combined to form a resultant signal 57. The described circuit is of the high frequency cut-off type and, accordingly, high frequency component 56 is eliminated from the reproducer output until the amplitude of the signal is equal to that represented by the lines 58, at which point the cut-off frequency is sufficiently high, due to increasing signal amplitude, as to admit the component 56. Accordingly, between the lines 58, the signal consists of the wave 55 by itself, whereas, above and below the respective lines 58, the signal consists of the combined wave form represented by the sum of components 55 and 56. This distortion of the wave form produces no appreciable distortion of the incoming programs, however, and it may be substantially eliminated by operating the noise suppression circuit at an amplifier stage where the signal level is very high so that the amplitude represented by the distance between the lines 58 is only a small fraction of the total signal amplitude.

The distortion of the signal just described, which results from intermodulation of low frequency and high frequency signals, may be eliminated or substantially minimized by utilizing a balanced push-pull circuit of the type shown by Figure 4. This circuit cancels out even harmonics together with the great majority of the intermodulation distortion components so that the noise suppression circuit functions in the manner already described without, however, the presence of distortion produced by intermodulation. In the figure, this circuit is shown as a coupling link having a signal gain of unity so that it may be inserted into existing amplifiers without extensive rearrangement of the amplifier circuit. The push-pull unit comprises an input transformer 60 having a primary winding 61 connected to input terminals 62 and 63, which are shunted by a potentiometer 64. The transformer 60 has a center tapped secondary winding 65, the tap being grounded by a conductor 66. One terminal of the secondary winding is connected to ground through three series-connected non-linear resistances 67, 68, 69 and the other secondary terminal is grounded through three series-connected non-linear resistances 71, 72, 73. A grounded condenser 75 is connected to the junction between resistances 61, 69; a grounded condenser 76 is connected to the junction between resistances 67, 61; a grounded condenser 77 is connected to the junction between resistances 72, 73; and a grounded condenser 78 is connected to the junction between resistances 71, 72. The junction between resistances 68, 69 is connected by a lead 80 to the control grid of a triode 81 and the junction between resistances 72, 73 is connected by a lead 82 to the control grid of a triode 83. The cathodes of tubes 81, 83 are interconnected by a lead 85 and grounded through a bias resistor 86. The anodes of the tubes are connected, respectively, to opposite terminals of a split secondary winding 87 of an output trans-

former 88, the center tap of this winding being connected to a positive power supply terminal 89. The secondary winding 90 of transformer 88 is shunted by a potentiometer 91, one end terminal and the arm of this potentiometer being connected, respectively, to output terminals 92 and 93.

This circuit functions in a manner similar to that of Figure 1 in that signal voltage of one phase is applied to the series-connected resistors 67, 68 and 69 while signal voltage of the opposite phase is applied to the resistors 71, 72 and 73, the output voltage appearing at the control grids of tubes 81 and 83. Each unit of the circuit consists essentially of a three stage low pass filter, the values of the resistances and, hence, the cut-off frequency being varied by the direct voltage component of the signal. Due to the push-pull circuit arrangement, difficulties resulting from intermodulation are eliminated or substantially minimized. The two potentiometers 64 and 91 are ganged so that they rotate as a unit. These resistances do not function simply as gain controllers but, rather, potentiometer 64 controls the level at which operation of the noise suppression unit is initiated. That is, this potentiometer controls the level of the incoming signal and, hence, the frequency at which attenuation of the signal begins. The function of the gain control may be performed by a conventional volume control in a subsequent stage of the amplifier. It will be understood that suitable impedance matching devices may be added to or substituted for the potentiometers 64, 91 to avoid impedance matching problems with the components of existing amplifiers, when it is desired to add the noise suppression unit to such amplifiers.

In Figure 5, I have disclosed a circuit which has been tested and found to give superior results in operation of a phonograph reproducer. This circuit includes three non-linear resistances 95, 96, 97 and a fourth resistor 98 all connected in series between the cathode of tube 10 and a ground terminal 99. An impedance 100 is connected between a ground terminal 101 and the junction between resistances 95 and 96, while a second impedance 103 is connected between a ground terminal 104 and the junction between resistances 96 and 97. Output terminals 106 and 107 are connected across resistance 97, and resistor 98 forms, together with a condenser 108, an integrating circuit which is connected to an amplifier-rectifier circuit similar to that described by Figure 1 through a lead 109. The present circuit is adapted to cut off unwanted high frequency signals and, accordingly, the impedances 102, 103 are condensers.

This circuit functions in a similar manner to that of Figure 1 in that signal voltage is applied to the series connected resistors 95 to 98, inclusive, from the cathode of tube 10 while a direct voltage representative of average signal amplitude is applied to the resistors 95, 96 and 97 from integrating circuit 98 and 108. The output voltage appears across resistor 97. It will be apparent that the noise suppression unit consists essentially of a two-stage low pass filter, the values of the resistances and, hence, the cut-off frequency being varied by the direct voltage impressed thereon by the integrating circuit 98 and 108. In operation, the attenuation of the present circuit is twelve decibels per octave above the cut-off frequency rather than six decibels per octave, as in the circuit of Figure 3. This attenuation is ample to eliminate most of the unwanted

high frequency components from the output of a radio or record reproducer.

While the invention has been described in connection with a present, preferred embodiment thereof, it is to be understood that this description is illustrative only and is not intended to limit the invention, the scope of which is defined by the appended claims.

Having described my invention, I claim:

1. In a noise suppression circuit, a band pass filter comprising a non-linear resistance, a second non-linear resistance connected in series with said first resistance, said resistances having similar voltage-resistance characteristics, and an impedance for by-passing alternating voltages appearing across one of said resistances, means for applying a voltage representative of signal amplitude across both of said resistances, and means for withdrawing an output appearing across one of said resistances whereby the pass band of said filter varies in accordance with signal amplitude responsive to changes in the ohmic value of said resistances resulting from changes in signal amplitude.

2. In a noise suppression circuit, a unit comprising a non-linear resistance and an impedance for by-passing alternating voltages appearing across said resistance, a second non-linear resistance connected in series with said first resistance, said resistances having similar voltage-resistance characteristics, means for applying a voltage representative of signal amplitude across both of said resistances whereby the voltage drop across the by-passed resistance is varied in accordance with frequency by said impedance to attenuate signals within a preselected frequency range, and the impressed voltage across said resistances varies the ohmic value thereof to shift said preselected frequency range in accordance with the signal amplitude, and means for withdrawing an output appearing across one of said resistances.

3. In a noise suppression device, a circuit comprising a non-linear resistance, and a unit including an impedance and a second non-linear resistance connected in parallel, said second resistance being connected in series with said first resistance, said resistances having similar voltage-resistance characteristics, whereby the impedance of said unit has a predetermined ratio to the total impedance of said circuit at frequencies where said impedance is large compared to said second resistance, and a substantially smaller ratio at other frequencies where said impedance is small compared to said second resistance, means for applying a voltage across said resistances which is representative of signal amplitude whereby the ohmic value of said resistances varied in accordance with the signal amplitude, thereby to shift the frequency range wherein said impedance is small compared to said shunted resistance in accordance with the signal amplitude, and means for withdrawing an output appearing across one of said resistances.

4. In a noise suppression device, a circuit comprising a non-linear resistance and a unit including an impedance, and a second non-linear resistance shunted across said impedance and connected in series with said first resistance, said resistances having similar voltage-resistance characteristics, means for applying a signal voltage across said resistances, the resultant signal voltage appearing across said resistance impedance unit being proportional to the ratio between the total impedance of said unit and the total im-

pedance of said circuit, said resultant voltage being substantially attenuated at frequencies where said impedance is small as compared to said shunted resistance, and said resultant voltage being substantially unattenuated at other frequencies, means for applying a direct voltage across said resistances which is proportional to the average amplitude of the signal, thereby to change the ohmic value of said resistances and shift the frequency band within which said resultant voltage is attenuated in accordance with signal amplitude, and means for withdrawing an output appearing across one of said resistances.

5. In a noise suppression device, an electron tube having an anode, a cathode, and a control grid, means for supplying operating potentials to the electrodes of said tube, means for applying a signal voltage to said control grid, a noise suppression circuit and an integrating circuit connected in series in the anode-cathode circuit of said tube, said noise suppression circuit including a non-linear resistance, an impedance for by-passing alternating voltages appearing across said resistance, and a second non-linear resistance connected in series with said first resistance, said resistances having similar voltage-resistance characteristics, said integrating circuit including a resistance and a condenser connected in shunt therewith, means for amplifying and rectifying the signal voltage, and means for applying the rectified voltage to said integrating circuit, thereby to apply a direct voltage to the noise suppression circuit which is proportional to the average signal amplitude, whereby the resultant signal amplitude across said first resistance is attenuated by a decrease in the reactance of said impedance at all frequencies within a preselected frequency range, and the impressed direct voltage across said non-linear resistances varies the ohmic value thereof to shift said preselected frequency range in accordance with the signal amplitude.

6. In a noise suppression circuit, a unit comprising a first non-linear resistance, an impedance for by-passing alternating voltages appearing across said first resistance, a second non-linear resistance connected in series with said first resistance, said resistances having similar voltage-resistance characteristics, means for applying a signal voltage across said series connected resistances whereby the signal amplitude across said resistance-impedance unit is varied in accordance with frequency by said impedance to attenuate signals within a preselected frequency range, the instantaneous signal voltage across said series connected resistances varying the ohmic value thereof to shift said preselected frequency range in accordance with the signal amplitude, and means for withdrawing an output appearing across one of said resistances.

7. In a noise suppression device, three non-linear resistances connected in series and having similar voltage-resistance characteristics, a pair of impedances for by-passing potentials appearing at the respective junctions between said resistances, means for applying a voltage representative of signal amplitude across said resistances whereby the voltage drop across one of said resistance units is varied in accordance with frequency by said impedances to attenuate signals within a preselected frequency range, and the impressed voltage across said resistances varies the ohmic value thereof to shift said preselected frequency range in accordance with the signal amplitude, and means for withdrawing an

output appearing across one of said resistances.

8. In a noise suppression circuit, a low pass filter comprising a pair of non-linear resistances connected in series and having similar voltage-resistance characteristics, and a condenser for by-passing high frequency voltages appearing across one of said resistances, means for applying a voltage representative of signal amplitude across both of said resistances to vary the cut-off frequency of said filter in response to resistance variations produced by said voltage in said non-linear resistances, the cut-off frequency increasing with increasing signal amplitude and decreasing with decreasing signal amplitude, and means for withdrawing an output appearing across one of said resistances.

9. In a noise suppression device, a circuit comprising a non-linear resistance, and a unit including a condenser, and a second non-linear resistance shunted across said condenser, said second resistance being connected in series with said first resistance, said resistances having similar voltage-resistance characteristics, means for applying a voltage representative of signal amplitude across said resistances, the resultant voltage appearing across said resistance-condenser unit being proportional to the ratio between the total impedance of said unit and the total impedance of said circuit, said resultant voltage being substantially attenuated by said condenser at frequencies above a preselected cut-off frequency at which the reactance of said condenser is equal to the impedance of the resistance shunted thereacross, the ohmic value of said resistances varying in accordance with the average amplitude of the signal whereby the ohmic value of said resistances is decreased as the signal amplitude is increased, thereby to raise the cut-off frequency at which the reactance of said condenser equals the lower impedance of the resistance shunted thereacross, and the ohmic value of said resistances is increased as the signal amplitude is decreased, thereby to lower said cut-off frequency, and means for withdrawing an output appearing across one of said resistances.

10. In a noise suppression device, a circuit comprising a non-linear resistance and a unit including a condenser, and a second non-linear resistance shunted across said condenser and connected in series with said first resistance, said resistances having similar voltage-resistance characteristics, means for applying a signal voltage across said resistances, the resultant signal voltage appearing across said resistance-condenser unit being proportional to the ratio between the total impedance of said unit and the total impedance of said circuit, said resultant voltage being substantially attenuated by said condenser at frequencies above a preselected cut-off frequency at which the reactance of said condenser is equal to the impedance of the resistance shunted thereacross, means for applying a direct voltage across said resistances which is proportional to the average amplitude of the signal whereby the ohmic value of said resistances is decreased as the signal amplitude is increased, thereby to raise the cut-off frequency at which the impedance of said condenser is equal to the lower impedance of the resistance shunted thereacross, and the ohmic value of said resistances is increased as the signal amplitude is decreased, thereby to lower the cut-off frequency, and means for withdrawing an output appearing across one of said resistances.

11. In a noise suppression circuit, an electron

tube having an anode, a cathode, and a control grid, means for supplying operating potentials to the electrodes of said tube, means for applying a signal voltage to said control grid, a noise suppression circuit and an integrating circuit connected in series in the anode-cathode circuit of said tube, said noise suppression circuit including a non-linear resistance, a condenser for by-passing high frequency voltages appearing across said resistance, a second non-linear resistance connected in series with said first resistance, said resistances having similar voltage-resistance characteristics, said integrating circuit including a resistance and a condenser connected in shunt therewith, means for amplifying and rectifying the signal voltage, and means for applying the rectified voltage to said integrating circuit, thereby to apply a direct voltage to the noise suppression circuit which is proportional to the average signal amplitude, whereby the signal amplitude across said first resistance is attenuated by said condenser at all frequencies above a preselected cut-off frequency, and the impressed direct voltage across said non-linear resistances raises the cut-off frequency as the signal amplitude increases and lowers the cut-off frequency as the signal amplitude decreases.

12. In a noise suppression device, an electron tube having an anode, a cathode, and a control grid, means for supplying operating potentials to the electrodes of said tube, means for applying a signal voltage to said control grid, a noise suppression circuit and an integrating circuit connected in series in the anode-cathode circuit of said tube, said noise suppression circuit including three non-linear resistances connected in series and having similar voltage-resistance characteristics, and a pair of condensers connected to the respective junctions between said resistances to by-pass signal voltages appearing at said junctions, said integrating circuit including a resistance and a condenser connected in shunt therewith, means for amplifying and rectifying the signal voltage, and means for applying the rectified voltage to said integrating circuit, thereby to apply a direct voltage to the noise suppression circuit which is proportional to the average signal amplitude, whereby the signal amplitude across one of said resistances is attenuated by said condensers at all frequencies above a preselected cut-off frequency, and the impressed direct voltage across said non-linear resistances raises the cut-off frequency responsive to increases in signal amplitude and lowers the cut-off frequency responsive to decreases in signal amplitude.

13. In a noise suppression circuit, a high pass filter comprising a pair of non-linear resistances connected in series and having similar voltage-resistance characteristics, an inductance for by-passing low frequency signals appearing across one of said resistances, and means for applying a voltage representative of signal amplitude across said resistances whereby the ohmic value of said resistances varies inversely with signal amplitude to change the cut-off frequency of said filter, and means for withdrawing an output appearing across one of said resistances.

14. In a noise suppression circuit, a unit comprising a non-linear resistance and an inductance for by-passing alternating voltages appearing across said resistance, a second non-linear resistance connected in series with said first resistance, said resistances having similar voltage-resistance characteristics, means for applying a

voltage representative of signal amplitude across said resistances whereby the voltage drop across said resistance is varied by said inductance to attenuate signals having a frequency lower than a preselected cut-off frequency, and the impressed voltage across said resistances varies the ohmic value thereof to lower the cut-off frequency as the signal level increases and to raise the cut-off frequency as the signal level decreases, and means for withdrawing an output appearing across one of said resistances.

15. In a noise suppression circuit, an electron tube having an anode, a cathode, and a control grid, means for supplying operating potentials to the electrodes of said tube, means for applying a signal voltage to said control grid, a noise suppression circuit and an integrating circuit connected in series in the anode-cathode circuit of said tube, said noise suppression circuit including a non-linear resistance and an inductance for by-passing low frequency voltages appearing across said resistance, and a second non-linear resistance connected in series with said first resistance, said resistances having similar voltage-resistance characteristics and equal ohmic values, said integrating circuit including a resistance and a condenser connected in shunt therewith, means for amplifying and rectifying the signal voltage, and means for applying the rectified voltage to said integrating circuit, thereby to apply a direct voltage to the noise suppression circuit which is proportional to the average signal amplitude, whereby the signal amplitude across said first resistance is attenuated by said inductance at all frequencies below a preselected cut-off frequency, and the impressed direct voltages across said non-linear resistances lowers the cut-off frequency as the signal amplitude increases and raises the cut-off frequency as the signal amplitude decreases.

16. In a noise suppression circuit, an electron tube having an anode, a cathode, and a control grid, means for supplying operating potentials to the electrodes of said tube, means for applying a signal voltage to said control grid, a noise suppression circuit and an integrating circuit connected in series in the anode-cathode circuit of said tube, said noise suppression circuit including three non-linear resistances connected in series and having similar voltage-resistance characteristics, a pair of by-pass inductances connected to the respective junctions between said resistances to by-pass a portion of the signal voltages appearing at said junction, said integrating circuit including a resistance and a condenser connected in shunt therewith, means for amplifying and rectifying the signal voltage, and means for applying the rectified voltage to said integrating circuit, thereby to apply a direct voltage to the noise suppression circuit which is proportional to the average signal amplitude, whereby the signal amplitude across one of said resistances is attenuated by said inductances at all frequencies below a preselected cut-off frequency, and the impressed direct voltage across said non-linear resistances lowers the cut-off frequency as the signal amplitude increases and raises the cut-off frequency as the signal amplitude decreases.

17. In a noise suppression circuit, two units connected in push-pull circuit arrangement, each of said units being constructed in accordance with claim 6, means for applying a signal voltage of one phase across one of said units, means for applying a signal voltage of opposite phase across

the other unit, and means for taking off output voltage of one phase from one of the resistances in one unit and for taking off output voltage of opposite phase from one of the resistances of the other unit.

5 18. The combination in accordance with claim 6 wherein said impedance comprises a condenser whereby the signal amplitude across said resistance-condenser unit is attenuated by said condenser at all frequencies above a preselected cut-off frequency and the impressed voltage across said resistances varies the ohmic value thereof to raise the cut-off frequency as the signal level increases and to lower the cut-off frequency as the signal level decreases.

10 19. The combination in accordance with claim 6 wherein said impedance comprises a condenser whereby the signal amplitude across said resistance-condenser unit is attenuated by said condenser at frequencies above a preselected cut-off frequency where the reactance of said condenser is equal to the impedance of the resistance shunted thereacross, and the instantaneous signals voltage across said resistances increases the ohmic value thereof as the signal amplitude decreases, thereby to lower the cut-off frequency at which the reactance of said condenser equals the higher impedance of said shunted resistance, and said instantaneous signal voltage decreases the ohmic value of said resistances as the signal amplitude increases, thereby to raise the cut-off frequency.

15 20. The combination in accordance with claim 7 wherein each of said impedances comprises a condenser whereby the signal amplitude across one of said resistances is attenuated by said condenser at frequencies above a preselected cut-off frequency where the reactance of said condenser bears a predetermined relation to the impedance of said resistances, the voltage across said resistances varying in accordance with the amplitude of said signal to lower the cut-off frequency responsive to a decrease in signal amplitude and to raise the cut-off frequency responsive to an increase in signal amplitude.

20 21. In a noise suppression circuit, two units each constructed in accordance with claim 20, means for applying a signal voltage of one phase across one of said units, means for applying a signal voltage of opposite phase across the other of said units, a pair of electron tubes connected in push-pull circuit arrangement, each having an anode, a cathode, and a control grid, means for applying operating and bias potentials to the electrodes of said tubes, means connecting a junction between two resistances of one unit to one of said control grids, means connecting a junction between two resistances of the other unit to the other of said control grids, an output transformer, and means connecting the anodes of said electron tubes to said output transformer.

25 22. In a noise suppression circuit, two units connected push-pull circuit arrangement, each of said units being constructed in accordance with claim 20, means for applying a signal voltage of one phase across one of said units, means for applying a signal voltage of opposite phase across the other unit, and means for taking off an output voltage of one phase from one of the resistances in one unit and for taking off out-put voltage of opposite phase from one of the resistances of the other unit.

23. The combination in accordance with claim 6 wherein said impedance comprises an inductance whereby the signal amplitude across said

resistance-inductance unit is attenuated by said inductance at frequencies above a preselected cut-off frequency where the reactance of said inductance is equal to the impedance of the resistance shunted thereacross, and the instantaneous signal voltage across said resistances increases the ohmic value thereof as the signal amplitude decreases, thereby to lower the cut-off frequency at which the reactance of said inductance equals the higher impedance of said shunted resistance, and said instantaneous signal voltage decreases the ohmic value of said resistances as the signal amplitude increases, thereby to raise the cut-off frequency.
